US00D900540S

(12) **United States Design Patent** (10) **Patent No.:** **US D900,540 S**
(45) **Date of Patent:** **** Nov. 3, 2020**

(54) **LID FOR A CONTAINER**

(71) Applicant: **Runway Blue, LLC**, Alpine, UT (US)

(72) Inventors: **Steven M. Sorensen**, Alpine, UT (US);
David O. Meyers, East Layton, UT (US)

(73) Assignee: **Runway Blue, LLC**, Alpine, UT (US)

(**) Term: **15 Years**

(21) Appl. No.: **29/733,191**

(22) Filed: **Apr. 30, 2020**

Related U.S. Application Data

(63) Continuation of application No. 29/650,949, filed on Jun. 11, 2018, which is a continuation of application No. 29/525,379, filed on Apr. 29, 2015, now Pat. No. Des. 820,038.

(57) **CLAIM**

The ornamental design for a lid for a container, as shown and described.

DESCRIPTION

FIG. 1 is an upper perspective view of a lid for a container attached to an unclaimed container;

FIG. 2 is an upper perspective view of the lid for a container shown in FIG. 1;

FIG. 3 is a front view of the lid for a container shown in FIG. 1;

FIG. 4 is a back view of the lid for a container shown in FIG. 1;

FIG. 5 is a right side view of the lid for a container shown in FIG. 1;

FIG. 6 is a left side view of the lid for a container shown in FIG. 1;

FIG. 7 is a top view of the lid for a container shown in FIG. 1; and,

FIG. 8 is a bottom view of the lid for a container shown in FIG. 1.

The broken lines showing a container in FIG. 1 depict environment and form no part of the claimed design. All other broken lines in the figures illustrate portions of the lid for a container that form no part of the claimed design.

1 Claim, 6 Drawing Sheets
